(57) **CLAIM**

The ornamental design for a sandal strap and locking sockets assembly, as shown and described.

DESCRIPTION

FIG. 1 is a perspective, front, left side view of a sandal according to the present invention;

FIG. 2 is an exploded perspective, front, left side view thereof;

FIG. 3 is an isolated top plan view of the sandal strap of FIG. 1 shown without the sandal sole;

FIG. 4 is an isolated bottom plan view of the sandal strap of FIG. 1 shown without the sandal sole;

FIG. 5 is an isolated front view of the sandal strap of FIG. 1 shown without the sandal sole;

FIG. 6 is an isolated rear view of the sandal strap of FIG. 1 shown without the sandal sole;

FIG. 7 is an isolated right side view of the sandal strap of FIG. 1 shown without the sandal sole;

FIG. 8 is an isolated left side view of the sandal strap of FIG. 1 shown without the sandal sole;

FIG. 9 is an isolated top view of the sandal sole of FIG. 1 shown without the sandal strap;

FIG. 10 is an isolated bottom view of the sandal sole of FIG. 1 shown without the sandal strap;

FIG. 11 is an isolated front view of the sandal sole of FIG. 1 shown without the sandal strap;

FIG. 12 is an isolated rear view of the sandal sole of FIG. 1 shown without the sandal strap;

FIG. 13 is an isolated left side view of the sandal sole of FIG. 1 shown without the sandal strap; and,

FIG. 14 is an isolated right side view of the sandal sole of FIG. 1 shown without the sandal strap.

The broken lines shown in the drawing views depict portions of the sandal that form no part of the claimed design.

1 Claim, 14 Drawing Sheets
